UNITED STATES PATENT OFFICE.

THEODORE C. BRECHT, OF WASHINGTON, DISTRICT OF COLUMBIA.

DESIGN FOR A PAPER-CUTTER.

SPECIFICATION forming part of Design No. 15,764, dated February 3, 1885.

Application filed December 30, 1884. Term of patent 7 years.

To all whom it may concern:

Be it known that I, THEODORE C. BRECHT, a citizen of the United States, residing at Washington, in the District of Columbia, have invented and produced a new and original Design for Paper-Cutters, Paper-Weights, &c., of which the following is a specification, reference being had to the accompanying drawings, forming part thereof.

- 10 In said drawings, Figure 1 represents a front elevation of my improved design for paper-cutter, &c. Fig. 2 is a rear elevation of the same. Fig. 3 is a cross-section of the same on line *x x*.
- 15 Heretofore paper-cutters have been made of pieces of flat ivory, tin, wood, &c., and of plain form and shape.
- The leading feature of my design consists in the shape or configuration of the blade for 20 a paper-cutter, the same being a conventional representation of the "Washington" monument, the shaft and base being thus a flattened diamond-shaped cross-section, as indicated in

Fig. 3 of the drawings. The shaft A represents the proper proportions, and the base B has 25 front and rear inclined faces.

The design may be of any desired size and of any suitable material. It may also be provided with a hole and ring near the top. A handle, B', is provided at the base, as seen in 30 Figs. 1 and 2.

The whole design thus forms a very useful as well as neat ornament.

I claim--

The design for a paper-cutter, &c., herein 35 shown and described, the same consisting of a shaft or blade, A, mounted on a base, B, and having a handle, B', and being a conventional representation of the Washington monument, as set forth.

In testimony whereof I hereby affix my signature in presence of two witnesses.

THEODORE C. BRECHT.
